UNITED STATES PATENT OFFICE.

WILLIAM D. McCOY, OF NEW YORK, N. Y.

INDICATING, REGISTERING, RECORDING, AND CHECK-PRINTING MECHANISM.

1,239,708.

Specification of Letters Patent. Patented Sept. 11, 1917.

Application filed August 25, 1910. Serial No. 578,928.

To all whom it may concern:

Be it known that I, WILLIAM D. McCox, a citizen of the United States, residing at 239 Lenox Ave., New York, in the county of New York and State of New York, have invented certain new and useful Improvements in Indicating, Registering, Recording, and Check-Printing Mechanism, of which the following is a specification.

10 My invention relates to improvements in what are commonly termed cash registers.

The main object of the invention is to simplify the construction and operation of a machine of this character, enable it to be made of but few parts and to accomplish certain operations as more fully hereinafter set forth.

The mechanism as a whole is constituted so as to facilitate the carrying out of a system for identifying and tracing each separate transaction, that is, the record or detail strip and the checks as printed in the machine can always be located and compared with absolute certainty by reason of the simultaneously printed identification marks as hereinafter pointed out. Improvements will be found to relate particularly to:

1st. Mechanism for controlling and setting the indicating and other mechanism and displaying the amount and nature of each transaction together with the symbol of the operator.

2nd. Simplified operating mechanism whereby a great variety of variations in values may be indicated, registered, printed and recorded.

3rd. Mechanism for indicating the values set up and the character of various transactions and the symbol of the operator.

4th. Mechanism for registering and totaling the items.

5th. Mechanism for printing the record of transactions upon a record slip and upon checks in which the consecutive numbering of the items on the record slip and on the checks is effected for each transaction.

6th. Mechanism for printing the time and date of each transaction upon the checks.

7th. Mechanism for feeding individual checks automatically to the printing position and delivering the same after the completion of the printing.

8th. Mechanism for classifying and registering the various transactions and indicating the nature thereof.

It will be noted that the different mechanisms as herein constituted and assembled are designed to coöperate and do so co-act as to constitute with each other improved combinations for the purposes hereinafter set forth. It will be obvious hereinafter that certain of these different mechanisms in themselves constitute improvements in the art adapted to uses independently or in conjunction with other mechanism. Other improvements will be found to reside in the details of construction, the preferred form of which is herein illustrated.

In the particular form of mechanism shown and described in detail hereinafter there is a graduated scale for setting up cents items—zero, 5, 10, etc., to 95 arranged on a horizontal arc at the front of the machine. Beneath this arc is arranged a setting arm pivoted near the rear of the machine and adapted to swing in a horizontal plane. This arm carries at its front end an operating knob having upon it a scale or dial graduated from zero to 19 for setting up dollar items. To set up an item for a transaction the arm is swung horizontally till it comes directly beneath the proper number on the cents setting scale and the knob is rotated until the proper dollar number is brought directly beneath the cents setting scale.

The setting arm carries a push key which is movable longitudinally for affecting the indicator shutter, the registering mechanism, the drawer release and the printing operation. The indication is effected by means of a series of dials which are arranged on a common axis and are rotated when the setting arm and knob are set. The shutter is operated to display the proper indications when the push key is operated and conceals the indication as soon as the operating arm is again moved. The indicating dials are operated by a series of frames which are pivoted on the same vertical axis with the setting arm. The rear ends of these frames are connected to the indicating dials and the front ends of the frames carry the type for printing items on the record strip and the checks. The registering mechanism is carried by the setting arm. The cents registering parts are set when the arm is swung horizontally to set up the cents item and are operated when the push key is operated. The dollar registering mechanism is

set when the operating knob is rotated to set up a dollar item and is operated when the knob is set back to zero. When the total of cents items registered equals or exceeds a 5 dollar the dollar is carried forward or transferred to the dollar registering mechanism. The drawer is released when the push key is operated. The operation of a spring connected with a handle at the right of the machine throws the drawer open and raises the handle and the depression of the handle to 10 normal position effects the printing of the record strip and the check and the closing of the drawer. The record strip is fed automatically from left to right above the printing frames and the checks are fed automatically from the rear to the front beneath the printing frames. A series of printing wheels arranged below the path of motion 15 of the checks print the date and time of each transaction. Two series of automatic counting and printing wheels print consecutive numbers on the face of the record strip and on the top face of each check. Classification 20 mechanism is arranged at the right of the machine and consists of a series of counters adapted to be operated by a key so that the operators can keep track of the total number 25 of the different kinds of transactions which the machine is designed to record. The character of the transaction is indicated at the same time. Alignment devices are provided throughout for necessitating the proper operation of the setting arm and 30 knob and other parts prior to actual indication, registration or printing. Safety interlocking devices are also provided to make it necessary to complete each operation before it is possible to set up the mechanism for 35 another item. It will be obvious hereinafter that many of the details of construction may be varied in form and arrangement and substitution may be made within a wide range of equivalents without a departure 40 from the spirit and scope of the invention 45 claimed herein.

Figure 1, is a front view of a machine embodying the improvements of my invention, part of the casing and the cash drawer 50 being omitted, the setting arm and key being in its mid position and the indicators set for the amount of \$10.45 and symbol X and the classification being "paid out."

Fig. 2, is a plan view of the same, the 55 operating and setting arm being in its extreme left hand position set for an amount of 95 cents.

Fig. 3, is a partial vertical section and elevation taken from the left of Fig. 1 and 60 showing also a part of the cash drawer.

Fig. 4, is a vertical sectional view showing the connections between the indicating dials.

Fig. 5, is an enlarged vertical sectional 65 view and side elevation parts being broken away and showing on an enlarged scale

parts of the operating, registering and printing mechanism.

Fig. 6, is a vertical sectional view of parts of the registering mechanism taken longitudinally of the operating arm. 70

Fig. 7, is a rear view of a fragment of the operating knob showing the interlocking device.

Fig. 8, is a rear view of parts of the shutter or curtain and mechanism for operating the same together with a part of the mechanism for operating the indicating dials. 75

Fig. 9, is a detail view of the gears for transmitting motion from the units of cents dial to the tens or tens of cents dial, parts being broken away. 80

Fig. 10, is a rear view and partial section of the record strip feeding and operating mechanism. 85

Fig. 11, is a plan view of the check printing platen.

Fig. 12, is a left hand side view and elevation of part of the check printing and feeding mechanism in the position which 90 the parts occupy when the mechanism has been operated and corresponds to the open position of the drawer.

Fig. 12^a is a perspective view of an inking roller and its supporting frame. 95

Fig. 13, is a front view and partial section on the plane of the line A A of Fig. 6 showing details of the registering mechanism.

Fig. 14, is a similar section of the registering mechanism on the plane of the line B B of Fig. 6. 100

Fig. 15, is a detail side view of part of the mechanism for the carrying forward of dollars from the cents registering drum to 105 the dollar registering devices.

Fig. 16, is a right hand side view and partial section of parts of the mechanism for releasing the drawer from the classifying mechanism and showing the time clock and 110 part of the printing mechanism.

Fig. 17, is a plan view and partial section of parts of the check and record strip printing mechanism.

Fig. 18, is a horizontal sectional view of 115 parts of the check printing mechanism showing its connection with the time clock.

Fig. 19, is a detail perspective view of the cam for raising the platen for printing the record strip. 120

Fig. 20, is a bottom view of a check as printed and delivered from the machine.

Fig. 20^a is an edge view of a plate for printing special matter.

Fig. 21, is a left hand side view and partial section on the plane of the line C, C of Fig. 2 showing the parts of the classifying and counting mechanism and showing part 125 of the mechanism for operating the printing device and closing the drawer. 130

Fig. 22, is a perspective view and section of the classifying arm on the plane of the line D, D of Fig. 21.

Fig. 23, is a detail perspective view of a 5 check for retaining the reversing pawl and it is similar to the check employed in connection with the feeding of the inking tape or ribbon.

Fig. 24, is a plan view showing the double 10 pawl and adjacent parts for compelling operation of the push key in the main setting arm.

Fig. 25, is a perspective view of the double pawl of Fig. 24.

15 Fig. 26, is a perspective view of the feeding pawl of the inking ribbon mechanism.

Fig. 27, is a perspective view of the reverse device for the ribbon feed.

20 Fig. 28, is a vertical front sectional view and the projection of the check supply feeding mechanism.

Fig. 29, is a view of the under side of the check feeding device.

25 Fig. 30, is an upright sectional view of the same on the plane of the line E, E of Fig. 29.

Fig. 31, is a perspective view of the check discharging arm or "kicker".

30 Fig. 32, is a perspective view of a fragment of the supply check or magazine for containing the unprinted checks.

The parts 1, 2 and 3 together with the vertical shaft 4 constitute the principal supporting members of the frame of the machine. The segmental section 5 of the front 35 of the case is mounted on the bed-plate 6 which latter may serve as a portion of the case for the usual cash drawer 7.

40 The main setting arm 8 is pivoted near the rear on the vertical shaft 4 and has a flanged sleeve 9 at the front end. This sleeve 9 surrounds tube 10 which is mounted upon a hollow shaft 11 which carries the knob 12 at its front end. The segmental section 5 has a slot or opening 13 which guides the sleeve 9 and thus permits the main setting arm to be swung in a horizontal plane. A guard 13' carried by the sleeve 9 covers the rear of the opening 13. The machine as 45 herein illustrated is adapted to indicate, register and print for amounts varying by five cents from 5¢ to 95¢ and dollars from zero to 19.

50 For the purpose of setting the mechanism I have arranged numerals zero, 5, 10, 15, etc., to 95 along the upper beveled edge 14 of the segmental section 5 and numerals zero, 1, 2, 3, etc., to 19 around the beveled edge of the knob 12. The former may be called the 55 "cents setting scale" and the latter the "dollar setting dial". It will be obvious however that the mechanism might be adapted to other systems of money counting and that the cents setting scale might be arranged by 60 units from zero, 1, 2, 3, etc., and that the

dollar setting dial might be arranged for a larger or smaller amount. Normally the knob 12 is held from rotation by means of the projection 15 at the rear which engages in a notch 16 in the flanged sleeve 9 which 70 is not rotatable. The knob however is adapted to be pushed inward, that is, to the left as viewed in Fig. 5, a distance sufficient to disengage the projection 15 from the notch 16 and allow the knob 12 to be rotated. It will be noted that when the knob is rotated it cannot be pulled outward until it is rotated back to its normal position at which position the zero on the dollar setting dial will be uppermost and adjacent the 75 cents setting scale. The flanged sleeve 9 carries a stop 17 to prevent the knob 12 from being turned more than one complete revolution.

At its rear end the setting arm 8 has a 80 projection 18 which is connected to a collar 19 pivotally mounted on the shaft 4 above the arm. This collar at its front end carries printing frame 19' for printing cents items and at the rear end is connected to the 85 indicating mechanism as will be later described. The collar 20 also pivotally mounted on shaft 4 carries printing frame 20' at the front end for printing dollar items and at the rear is connected to operate the dollar 90 indicating dial. The collar 21 also pivotally mounted on the shaft 4 carries the operator's printing frame 21' and is connected at the rear to the operator's indicator. Connected to the collar 20 is a segmental beveled 95 gear 22 also pivoted on shaft 4 with which the bevel pinion 23 carried by the hollow shaft 11 is adapted to engage when the shaft and knob 12 are pushed to the rear, that is, 100 to the left as viewed in Fig. 5. The spring 105 pawl 24 engages notches 25 in the upper face of gear 22 so as to assist in stopping the movement of the gear 22 at definite angular positions. A notched segment 26 beneath the setting arm 8 is adapted to assist 110 in definitely positioning the setting arm when the reciprocating frame 27 is pushed inwardly as will be later described, it being necessary that a part of the frame 27 should mesh with one of the notches in the segment 115 26 which notches correspond with the different cents amounts on the cents setting scale.

120 The amount indicated by the dials in Fig. 1 is \$10.45 and the operator's symbol X. The usual windows will of course be provided in the case for displaying the amounts and symbols but it is unnecessary to illustrate them herein. The shutter 28 is adapted to cover up the indicating portion of the 125 dials except when the machine is operated properly to indicate the definite amounts. The operation of the shutter will be described later. The dial 30 has printed around its periphery the alternating 130

amounts zero—5, zero, etc. This dial may be termed the "units indicating dial." The dial 31 has numerals zero, 1 to 9 inclusive and may be called the "tens indicating dial." The dial 32 has the numerals zero, 1, 2, to 19 inclusive and may be termed the "dollar indicating dial." The dial 30 is carried by the rotatable shaft 33 which has on its rear end pinion 34. An oscillating member 35 pivoted on a horizontal axis has a segmental gear 36 meshing with pinion 34 at its upper end and a segmental bevel gear 37 at its lower end meshing with the segmental bevel gear 38 at the rear of the collar 19. When the setting arm 8 is swung horizontally the collar 19 is swung correspondingly and by reason of the connection between the gears 38, 37 and 36, 34 the dial 30 is rotated correspondingly. Fig. 4 shows details of connection between the indicating dials. On the shaft 33 is a gear 40 meshing with gear 41 (see Fig. 9) which is carried by bracket 42. These two gears are similar to what is commonly known as Geneva gears for intermittent transmission. The gear 41 has gear 43 rotating with it and the latter meshes with gear 44 on a hollow shaft 45 which carries the indicating dial 31. The gears 40, 41 are so cut that the gear 41 has one rotation for every two rotations of gear 40 and its action is thus intermittent. The gear connection between the setting arm 8 and the shaft 33 and dial 30 is such that as the setting arm is moved from zero to 5 on the cents setting scale, the indicating dial 30 rotates so as to bring the numeral 5 in the indicating position, that is, one-tenth of a revolution. When the setting arm is moved from 5 to 10 on the cents setting scale the units indicating dial 30 moves to the next zero position one-tenth more of a revolution. The connection between the gears 40 and 41 is such therefore that at this time the gear 41 will make one-tenth of a turn and thus rotates the dial 31 one-tenth of a turn and thus brings numeral 1 on the tens dial into the indicating position. The movement of the indicating dials 30 and 31 is progressive as the setting arm is swung from right to left. The dollar indicating dial 32 is carried by a sleeve 46 which has a bevel pinion 47 meshing with a segmental bevel gear 48 which is carried by an upward extension 49 from the collar 20 before referred to. When the setting knob 12 and dollar setting dial are rotated, the pinion 23 rotates the gear 22, collar 20 and arm 49 which thus rotates the pinion 47 and dollar indicating dial 32 progressively. The symbol dial 50 is semi-circular and carried by sleeve 51 which has bevel pinion 52 meshing with segmental gear 53 on the arm 54 extending upwardly from collar 21. The frame 21' has a forward extension 55 with an operating knob or handle 56 so that the frame 21' may be swung from right to left to set the operator's symbol for indicating and printing. A scale may be provided for setting the handle 56 in a manner similar to the setting of the arm 8 at the different cents positions. The rear dial 50' is also semi-circular and connected to dial 50 by means of a web 57 so that the two rotate together. The dials are arranged in pairs so as to display corresponding indications at the front and rear simultaneously. Dial 30' is mounted on shaft 33 with dial 30. Dial 31' is on hollow shaft 45 with dial 31 and dial 32' is on sleeve 46 with dial 32.

The shutter 28 is carried by two up-right rods 60, 60 connected at their lower ends by a horizontal rod 61, these parts constituting the shutter frame. A pivoted pawl 62 constitutes a catch for holding the shutter in its raised position at which time figures on the indicating dial are visible. This pawl has a rearwardly and upwardly extending arm which by means of a spring 63 (see Fig. 8) is pressed upwardly against the notched lower surface 64 at the rear end of the collar 19 just beneath the segmental gear 38. The lower end of the pawl 62 has a notch or recess 65 in which the rod 61 of the shutter frame is supported when in the position shown in Figs. 3 and 8. A swinging frame 66 is loosely pivoted to the rod 61 with the shutter frame and has a shoulder 67 at the lower end which when the shutter is down rests upon the projection 68. This projection is a part of a vertically movable frame having the rear upright bolt 69 and the front up-right 70 connected by the cross-piece 71 (see Fig. 16). This vertically movable frame is guided by ball bearings or other suitable means of connection on the square post pillow block 72. The lower end of the rear up-right 69 is beveled and when the parts are in the position shown in Fig. 16 engages the catch 73 projecting from the rear of the drawer 7. This is also shown in Fig. 3. When the main setting arm 8 and collar 19 are moved to the right or left from the position shown in Figs. 3 and 8 the horizontal arm of the pawl 62 is forced downward by the action of the notched portion 64 of the collar 19 and the catch 65 is thus disengaged from the rod 61 and the shutter frame allowed to drop by gravity until the bracket 66 falls into the position in dotted lines in Fig. 3 at which time its shoulder 67 rests upon the projection 68 just above mentioned. The shutter is raised by the inward thrust of push key 75.

The rod 76 has a push key or thumb-piece 75 and is reciprocable in the hollow shaft 11 previously referred to as constituting a part of the main setting arm construction. A collar 77 securely fixed upon the rod 75 near its rear end engages an up-right por-

tion 78 of the main reciprocating frame 27 which is carried by the main setting arm 8. The spring 79 has its rear end secured to the reciprocating frame 27 and its front end connected to a screw 80 or other projection carried by the main setting arm 8, so that the spring places a tension upon the reciprocating frame 27 to hold it in and to return it to its forward position, that is, at the right as viewed in Fig. 5. The rear lower portion of the reciprocating frame 27 has an inclined or cam surface 81 adapted when the reciprocating frame is pushed inward to engage the corresponding inverted incline 82 on the vertically moving frame on the pillow block 72 before referred to. When the push key 75 is pushed inward the action of the incline 81 is to lift the vertically moving frame and its projection 68 and thus by means of the engagement of the latter with the shoulder 67 lift the indicator shutter 28 from the dotted line position of Fig. 3 to the full line position previously referred to. When the up-right bolt portion 69 of the vertically moving frame is disengaged from the latch 73 (see Figs. 3 and 16), the drawer is released.

The arm 83 carried by the shaft 84 has a normally forward pressure exerted upon it by the spring 85. Near the lower end of this arm 83 is a roller 86 carried by the drawer 7. When the drawer has been released as just mentioned, the power of the spring 85 thus throws the drawer forward. The completion of closing the drawer will be described in connection with the printing operation hereinafter.

In order to prevent improper operation I have provided a double acting pawl device which necessitates the push key 75 being pushed completely inward and then thrown completely forward by the action of the spring 79 and frame 27 when the key has been released (see Figs. 3, 5, 24 and 25). The body of the pawl device 87 is pivoted on a stud 88 carried by the reciprocating frame 27. This has an elastic or spring portion 89 tending to hold the pawl device in the position shown in Fig. 24. The rear end of the pawl device has oppositely faced teeth 90, 91. Between them is arranged a yielding or elastic projection 92. On the main setting arm 8 in the path of movement of the projection 92 is a cam member 93 having its opposite ends beveled as shown in Fig. 24. The opposite faces of the setting arm 8 adjacent this cam 93 have oppositely faced teeth 94 and 95 adapted to be engaged respectively by the teeth 90 and 91 of the pawl device. When the pawl device moves to the rear by reason of the pushing in of the push key 75 and reciprocating frame 27 the elastic projection 92 engages the front hand end of the cam 93 and is forced to the left (as viewed in a plan view of the ma-

chine). This brings the teeth of the pawl device into engagement with one of the teeth 95 in the main setting arm. The pawl device will yield sufficiently to allow the continued inward or backward movement of the operating key or pawl device but will not allow forward or return movement until the projection 92 is disengaged from the rear of the cam 93. As soon as the projection is thus disengaged from the rear of the cam 93 the spring 89 will return the pawl device to its central position so that the projection 92 will stand in the rear of the cam 93. If the push key is then released the action of the spring 79 will move the reciprocating frame 27 and the pawl tooth forwardly (to the right as viewed in Fig. 24). The rear end of the cam 93 will then be disengaged by the projection 92 and force the projection to the right (as viewed in plain view), thus tilting the pawl device so that the tooth 90 engages one of the teeth 94 on the main setting arm. It will thus be seen that the pawl device and operating key are free to continue their forward motion but cannot be pushed inward until the forward motion is completed because of the inter-engagement of the tooth 90 with the teeth 94.

The registering mechanism is shown particularly in Figs. 2, 5, 6, 13, 14 and 15. A segmental bevel gear 100 which is stationary is engaged by the teeth of a bevel gear 101. This latter has a hub 102 which is rotatably mounted upon the sleeve 103 on the hollow shaft 11. A star-wheel 104 carried by hub 102 is engaged by a roller 105 carried by a pair of arms 106 which are normally pressed by a spring 107 so as to hold the roller 105 in one of the spaces between the teeth of the star-wheel 104. This roller 105 and its arms 106 are adapted to yield as the star-wheel is rotated by reason of the lateral swinging of the main setting arm 8 and hollow shaft 11 but the tendency of the pressure of the roller 105 is to stop the rotation of the star-wheel 104 and consequently to stop the swinging of the shaft 11 at one of the positions corresponding to one of the setting points on the cents setting scale. The sleeve 103 has a cam groove 108 in which a pin 109 on the reciprocating frame 27 projects. The sleeve 103 is rotatable on the hollow shaft 11 but is prevented from rearward motion by the sleeve 110. When the key 75 is pressed inward and carries with it the reciprocating frame 27 as above mentioned, the pin 109 by reason of its engagement in the cam groove 108 causes rotation of the sleeve 103 through nearly a complete revolution. The cents registering drum 111 is carried by a ratchet 112 which is rotatable on the hollow shaft 11 (see Fig. 6). Mounted on the sleeve 103 is a plate 113 which is connected to the web of the bevel gear 101 by means of a spring 114. A

6

spring pressed pawl 115 carried by the plate 113 engages the teeth of the ratchet 112. Normally the spring 114 tends to rotate the plate 113 relative to the gear 101 until the 5 projection 116 on the plate 113 engages the stop 117 on the gear 101. The gear 101 as above mentioned rotates as the arm is moved from left to right and vice versa and the position of the stop 117 is therefore depend- 10 ent upon the position of the arm 8. The sleeve 103 has a flange 118 which has a shoulder 119 which rotates with the sleeve 103 as the key is pushed in and out. The spring 114 normally tends to rotate the plate 15 so that a part of it for instance, the hub of the pawl 115 presses against the stop 119. As the key 75 is pushed inward the sleeve 103 is rotated to the right as viewed from the front, or clockwise, by reason of the pin 20 109 in the cam groove 108 and the tension of the spring 114 will cause the plate 113 and pawl 115 to follow around to the right until the projection 116 on the plate 113 engages the stop 117 carried by the gear 101. 25 The amount of the rotation of the plate and its pawl 115 will therefore depend upon the angular position of the gear 101 and main setting arm 8. As the pawl 115 rotates to the right it slips over the teeth of the ratchet 30 112 and when the key is released the pawl returns and rotates the ratchet 112 and the cents setting drum 111 through exactly the angle that the displacement of the stop 117 permitted the plate 113 and the pawl 115 to 35 rotate when the key was pushed inwardly. This then brings the proper number on the cents registering drum to the reading position which in this particular arrangement is selected to be at the upper surface of the 40 drum. The spring pawl 120 engaging with the notch or ratchet-like periphery of the registering drum 111 prevents the drum from being turned backwardly (see Figs. 14 and 15).

45 Any suitable form of counting mechanism such as 121 may be employed for keeping track of the total number of dollars registered. This is driven by the plate 122 by the operation of the knob 12 and intermediate mechanism. Normally the plate 122 is held stationary by a projection or finger 123 carried by the reciprocating frame 27 engaging in a notch in plate 122 (see Fig. 13). The plate 122 carries a spring pressed 50 pawl 124 engaging with the teeth of the ratchet 125. The latter is pinned or otherwise suitably secured to a gear 126 which meshes with a pinion 127 on the shaft of the counting mechanism. On the rear end 55 of the tube 10 previously referred to is a plate 128 which is connected by means of a spring 129 to the hub of the plate 122. The tension of this spring holds the nose 130 of the plate 128 against the projection 60 131 carried by the plate 122. The tube 10 has a flange at its front end carrying a pin 132 adapted to register with the recess 133 in the rear of the operating knob 12 when the knob has the zero on its dial uppermost. When the knob 12 is pushed in (see Fig. 5) 70 the pin 132 engages the recess 133 and thereupon the rotation of the dial 12 will be communicated to the tube 10 and the plate 128 on its rear end. The plate will thereupon be rotated through an angle corresponding 75 to the number of dollars of the item to which the dollar setting dial is set. The pinion 23 at this time is in mesh with gear 22 which is yieldingly held in position by means of the spring pressed pawl 24 operating in conjunction with the notches 25 heretofore referred to. When the push key 75 is pushed inward and carries with it the reciprocating frame 27, the finger 123 is disengaged from the notch in the edge of the plate 122 and 80 passes to the rear leaving the plate 122 free to be rotated in a right hand direction as viewed from the front of the machine. In this right hand rotation caused by the tension of the spring 129 the pawl 124 rides 85 over the backs of the ratchet teeth 125 until the rotation of the plate 122 is stopped by the engagement of the stop 131 with the nose 130 on the plate 128 which is the angular distance corresponding to the number 90 of dollars of the item set up. When the push key 75 is released the reciprocating frame 27 moves forward again and the finger 123 engages the teeth of the ratchet 134 on the rear of the plate 122, thus preventing the 95 plate 122 from being rotated to a higher registration. When the knob 12 is rotated left handed back to the zero position the finger 123 rides over the back of the teeth 100 of the ratchet 134 cut in the rear of plate 122 until it comes opposite the notch in the edge of the plate 122 whereupon it engages and locks the plate. When the knob 12 and plate 122 are rotated backwardly as just mentioned, the pawl 124 being in engagement with the ratchet 125 rotates the ratchet and its attached gear 126 and the pinion 127 of the counting mechanism through angles corresponding to the dollar item which has been set up. It will be noted in this particular that by reason of the interaction of the finger 123 on the reciprocating frame 27 with the teeth 134 on the back of the plate 122 that the operation of the machine is completely locked until the knob 12 is turned 110 backward to its zero position and the registration set up has been completed. Until this takes place the machine cannot be further operated, since when the frame 27 is in this rearward position it is interlocked 115 with the stationary notched segment 26 previously referred to. 120 When the cents registering drum 111 has been advanced to 95¢ the next registration 125 will carry forward or transfer the next item 130.

to the counting mechanism. Figs. 5, 6, 13, 14 and 15 show the details of this device. Beneath the drum 111 and plate 122 is located the short shaft 135 suitably pivoted on 5 the main setting arm 8. At the rear end this shaft carries an upwardly projecting arm 136 which stands in the path of movement of the pin 137 which projects rearwardly from the drum 111. The front end 10 of the shaft 135 carries a pawl arm formed in two parts 138 and 139 which are pivotally connected together. A spring 140 exerts a pressure upon the two parts of the arm in connection with the shaft 135 so as to hold 15 the upper end of the part 139 which is hooked as shown in Fig. 13 in engagement with the teeth of the pinion 126 previously referred to. When the registering drum 111 moves forward from the 95¢ registering 20 position to the zero position making a total of \$1.00 on the cents registering mechanism, the pin 137 strikes the arm 136 and moves it to the right, as viewed from the front of the machine; so as to rock the shaft 135 25 and arm 138 and carry the pawl part 139 to the right. This rotates the ratchet 125 and the gear 126 secured thereto and the latter being in engagement with the pinion 127 moves the dollar counting dial forward 30 one point. As soon as the pin 137 is past the arm 136 the latter under the pull of spring 140 snaps back into its proper position ready for the carrying forward of the next dollar from the cents registering drum.

35 It will be noted that the cents registration occurs while the reciprocating frame 27 is being thrown forward by the spring 79 after release of the push key 75 and the dollar registration occurs while the knob 12 is being turned back to the zero position of the dollar setting dial. As the carrying forward of the total of one dollar from the cents registration drum to the dollar registration device occurs when the cents registration takes place there is no possibility of interference between the carrying forward operation and the regular operation of dollar registration from the operating knob.

40 The record or detail strip 145 is of any ordinary or suitable character and in the form shown is provided in a roll on the spool 146 and is wound on to the hub 147 traveling from left to right as viewed from the front of the machine (see Fig. 1). The hub 147 is hollow and mounted upon the stationary spindle 148 (see Fig. 10). Secured to the hub is the ratchet 149 engaged by the spring pressed pawl 150. A vertically reciprocable member 151 (which also constitutes the printing platen for pressing the record strip against the type) carries a, 45 spring finger 152 which is adapted to engage the teeth of the ratchet 149. A plate 50 153 has a portion cut away to provide guid-

ing and bearing surface for the end of the spring finger 152 so that the member 151 rotates the ratchet 149 at about the middle of its downward stroke and the finger 152 is disengaged from the ratchet at the lower 55 end of the stroke. On the upward motion of the member 151 and finger 152 the ratchet is held from backward rotation by the pawl 150 and the finger 152 is retracted by the sliding engagement with the curved edge 60 of the plate 153. The member 151 has a shoulder 154 at the lower end engaged by the cam 155 whereby the member 151 is raised as will be pointed out, and is pressed downward by the spring 151^a (see Fig. 1). 65

The cam 155 is mounted upon the sleeve 156 which is rotatable in suitable bearings in the part 3 of the frame of the machine (see Figs. 17 and 18). In the particular form shown the cam is secured to the case 70 157 of the time clock. The gear 158 rotatable with the cam and clock is in mesh with the segmental gear 159 which is secured on shaft 160 (see Fig. 16). This shaft 160 has an arm 161 connected by 75 means of link 162 to the arm 163 on shaft 84 previously referred to (see Fig. 3). The crank 164 on the right of the machine is secured to this shaft 84 and is normally nearly horizontal as shown in Figs. 1, 3 and 21, 80 being inclined slightly downward toward the rear. It should be noted however that the particular position or angle of inclination of the crank is immaterial and the position is referred to simply for the sake of 85 convenience of description. This crank 164 and the shaft 84 may be operated by any suitable driving means either manual or power but for convenience I have illustrated the crank 164 with a handle for the purpose 90 of operating the shaft 84.

In order to prevent errors and tampering with the machine I have provided means for necessitating the completion of the oscillation of the shaft 84 when once it has been 95 started in either direction. This is illustrated in Figs. 2 and 21. An arm 165 secured to shaft 84 carries the pivoted two-pronged pawl 166 which has a central tooth 167 engaging in one of the two notches 100 168 of the catch 169. This catch is carried by the arm 165 and it is under pressure of the spring 170 tending to hold the catch in engagement with the tooth 167 of the pawl. Two series of notches or ratchet teeth 171 105 and 172 are adapted to be engaged respectively with the upper and lower prongs of the pawl 166. The teeth are faced in opposite directions as shown in Fig. 21 and the intermediate shoulder 173 is provided. 110 When the crank 164 is moved upward from the position shown in Fig. 21 the pawl 166 is carried downward and allowed to slide over the backs of the teeth of the ratchet portion 171 but the shape of the teeth pre- 115 120 125 130

vents the pawl and arm from being returned to the original position until the pawl 166 is disengaged by the contact of its upper prong with the shoulder 173. This contact tilts the pawl 166 clock-wise sufficiently to force the tooth 167 of the pawl out of the upper notch of the catch 169, the catch yielding sufficiently to permit this. The tooth 167 then snaps into the lower notch of catch 169 where it is yieldingly held. The crank 164 may then be pushed downward and the arm 165 moved upward accordingly, the lower prong of the pawl 166 then sliding over the backs of the teeth of the ratchet portion 172. The crank 164 cannot be moved upward again until the lower spring of the pawl 166 engages the shoulder 173 and is forced backward into the position shown in Fig. 21, the tooth 167 snapping from the lower notch to the upper notch 168 in the catch 169.

Normally the drawer 7 is closed and latched by the bolt 69 engaging with the latch 73 as before referred to. When the reciprocating frame 27 is pushed inward and raises the bolt 69, the latch 73 is released and the spring 85 secured to shaft 84 exerts its pressure through the arm 83 and throws the drawer open at the same time raising the crank 164 and by means of the connection from the crank 163, link 162, crank 161, shaft 160, segmental gear 159 and pinion 158 rotates the cam 155 which lifts the platen member 151. As the cam rotates right-handed beyond the position shown in Fig. 16 the shoulder 154 is disengaged and the member is pulled downward by the spring 151 and the record strip is thus fed forward by the engagement of the finger 152 with the ratchet 149 which is secured to the winding hub. At the bottom of the stroke the printing takes place as will be understood hereinafter. When the crank 164 is pulled forward and downward again it moves the arm 83 to the rear. This latter by its engagement with the roller 174 at the rear of the drawer closes the drawer and at the same time releases the member 151 which is raised by the rotation of the cam 155 back to the position shown in Fig. 16 which is its normal position.

On the left of the pillow block 72 previously referred to is located a bolt 180 which has a limited forward and backward movement in or on suitable guides and is normally pressed forward by a spring 181 (see Fig. 3). The upright 70 of the vertically movable frame 71 on the pillow block is provided with a shoulder 182 adapted to engage the forward beveled end of the bolt 180 when the frame is raised by the action of the reciprocating frame 27. As the shoulder 182 passes above the bolt 180 the bolt snaps forward beneath the shoulder and thus prevents the frame from being moved

down under the impulse of the spring 183 (see Fig. 16). The rear of the bolt 180 has a shoulder 184 or lip which projects to the left and is adapted to be engaged by the arm 83 when that is moved rearwardly by the downward action of the crank 164. As the arm 83 is moved to the rear, to the rear dotted position shown in Fig. 3, the lip 184 is engaged by the arm and the bolt is retracted from beneath the shoulder 182 thus allowing the spring 183 and gravity to move the frame 71 downward. As the frame 71 moves downward the bolt 69 engages the catch 73 on the drawer and holds the drawer in its closed position. When the crank 164 is released the tension of the spring 85 rotates the shaft 84 until the arm 83 strikes the roller 86. It will thus be seen that the drawer 7 acts as a movable abutment for the arm 83. The bolt 69 serves to lock this movable abutment until the push key 75 is operated.

Normally the platen member 151 rests with its shoulder 154 upon the tip of the cam 155 as shown in Fig. 16. When the drawer 7, constituting the movable abutment as just mentioned, is released by the raising of the bolt 69 from the latch 73, the spring 85 turns the shaft 84 and the cam 155 through the medium of the mechanism above described. The cam thus rotates right-handed or clock-wise and the shoulder 154 of the platen member 151 is disengaged from the point of the cam, then drops to cause the printing, and is then gradually raised as the cam continues to rotate. The cam has its greatest radius at about the point 190 (see Figs. 16 and 19), which is somewhat greater than the radius of the cam at its tip directly beneath the shoulder 154 as shown in Fig. 16. A spring pressed catch 191 is adapted to snap beneath the shoulder 192 on the platen member 151 when the point 190 of the cam 155 raises the platen member to its highest position. The lower end of the catch 191 has a projection 193 at its rear whose upper and lower faces are inclined as shown in Fig. 16. An arm 194 carried by the vertically moving frame 71 has its front end beveled to co-act with the faces of the projection 193. When the frame 71 is moved upward to the inward travel of the reciprocating frame 27 the end of the arm 194 rides up the lower inclined face of the projection 193 and tilts the catch 191 until it comes above the upper inclined face of the projection 193, at which time the nose of the catch 191 is tilted to snap beneath the shoulder 192 on the platen member when the platen member is raised to its highest position by the high point 190 of the cam 155 coming beneath the shoulder 154. When the crank 164 is pulled forward and downward its first action is to oscillate the shaft 84 right-handed as viewed in Fig. 3 thus

thrusting the rod 162 forward and oscillating the crank 161 and shaft 160 left-handed as viewed in Fig. 3 and right-handed as viewed in Fig. 16 until the cam 155 is brought to the position shown dotted in Fig. 16 with the tip of the cam beneath the shoulder 154 on the platen member. Just at the completion of the downward forward movement of the crank 164 and the rearward movement of the arm 83 the lip 184 of the bolt 180 is engaged by the arm 83 and the bolt is retracted from the shoulder 182 on the vertically moving frame 71 which is at that instant forced downward by gravity and spring 183. The downward movement of the arm 194, by reason of the engagement of its forward beveled end with the projection 193, disengages the catch 191 from the shoulder 192 and permits the platen member 151 to be forced downward by the tension of the spring 151 into the position shown in Fig. 16 with the shoulder 154 resting on the tip of the cam.

The frame 19' has a segment 200 with type faces on its upper surface for printing on the record strip the zero, 5, 10, 15, etc., cents items and which are arranged in a circumferential position corresponding with the location of the figures on the cents setting scale. The frame 20' has a similar type segment 201 with type faces along its upper surface of zero, 1, 2, etc., corresponding to the dollar setting dial figures. The frame 21' has a similar type segment 202 carrying the type for printing the operators' symbols in line with the dollar and cents figures. Nearer the front of the machine than the type segments just described are somewhat similar type segments carried by the same frames but having type facing downward for printing on the checks. The frame 19' carries a type segment 203 with the check cents printing type. The frame 20' carries the segment 204 with the check dollar printing type. The frame 21' carries the segment 205 with the operator's symbol check printing type. These two sets of type segments are shown in front elevation Fig. 1, in plan view in Fig. 2 and section in Fig. 5. While the mechanism as previously described is provided with other alining mechanism I prefer also to provide additional means for insuring the perfect alinement of the type printing segments. For this purpose the segments 203, 204 and 205 are notched along their upper surfaces as shown in front view Fig. 1 and plan view in Fig. 2 in a manner similar to the notches of the gear segment 22 in Fig. 5 previously referred to. Above these segments adjacent the printing position is located a spring pressed plunger 206 adapted to engage in the notches in the upper surface of the type segments. The lower face of the plunger is beveled toward the right and toward the left to correspond with the beveled faced notches in the type segment 203 so that the plunger will find its proper seat in the notches and yet will allow the frames to be swung properly from side to side without too great resistance.

The inking ribbon is fed back and forth from one spool to another, the spools being of suitable character and mounted upon the shafts 210 and 211 (see Fig. 5). The ribbon 212 passes over the faces of the type segments 200, 201, 202 around the guide roller 213 at the rear, under the edge of the plate 214 and forward beneath the faces of the type on the segments 203, 204, 205 to the spool on shaft 211. The shafts 210 and 211 have ratchets 215, 216 respectively with teeth facing in opposite direction, for instance, (see Fig. 12). An arm 217 pivoted at 218 carries two yielding pawls 219 and 220 adapted to coöperate respectively with the ratchets 215 and 216. On the end of shaft 160 opposite the oscillating segment 159 is another oscillating segment 221. The pawl arm 217 is held in the position shown in Figs. 5 and 12 against the stop 222 by the spring 223. This pawl arm has a shoulder 224 adapted to be engaged by the nose 225 on the oscillating segment 221 when the latter is thrown into the position shown in Fig. 12 by the release of the drawer and the upward and backward movement of the operating crank 164. This oscillates the pawl arm 217 on its pivot 218 in a left-handed direction so that the pawl 220 rotates the ratchet 216 and thus winds up the ribbon on the lower forward spool shaft 211. When the operating crank 164 is pulled forward and downward and the oscillating segment 221 is moved from the position of Fig. 12 back to the position of Fig. 5, the pawl arm projection 224 is released and the spring 223 pulls the pawl arm back against the stop 222, the pawl 220 yielding over the backs of the ratchet teeth 216. The pawl arm 217 carries a reversing member shown in perspective in Fig. 27 and having two arms 226 and 227 adapted to be engaged by the ribbon on the winding spools when one or the other spool, as the case may be, becomes filled. The pawl arms are shown in perspective in Fig. 26. The pawl devices and reversing devices are pivotally mounted on the pin 228 (see Figs. 5 and 12). The tongue 229 on the pawl arm projects into a slot 230 on the reversing device so that the pawl and reversing devices are virtually secured together and have a common pivotal support on the arm 217. The pawl arm 217 carries a catch 231 with two notches adapted to be engaged by the tooth 232 on the reversing device. The catch 231 is pressed forward by a spring 233 and the co-action between the shoulder 232 and the catch 231 is substantially the same as the co-action be-

tween the pawl 166 and catch 169 shown in Figs. 21 and 23 and previously described. When the lower ribbon spool becomes filled the pressure of the ribbon against the reversing arm 227 tilts the reversing device until the tooth 232 snaps from the upper to the lower notch in the catch 231 thus throwing the pawl 220 out of engagement with the ratchet 216 and throwing the pawl into engagement with ratchet 215. Continued movement of the mechanism causes the ribbon to be fed in the opposite direction and wound upon the upper ribbon spool on shaft 210. The tongue 229 projects sufficiently to serve as a handle to effect the reverse movement, should such become necessary.

In order to provide a positive identification for the purpose of comparison between the checks and record strip I print on the successive checks consecutive numbers and adjacent each item on the record strip I print the corresponding consecutive numbers of the same items. This is accomplished by means of two sets of counter wheels of suitable construction, having printing type upon their faces instead of the ordinary visual display figures. These are shown particularly in Fig. 17. The printing wheels 235 are mounted on the shaft 236 which has a spring pressed arm 237 (Figs. 16 and 17) which is oscillated by the projection 238 on the shaft 160 attached near the left-hand end thereof. On the shaft 236 or secured to the units wheel is a bevel gear 239 meshing with the lower face of the double faced miter gear 240 whose upper face meshes with the gear 241 on the shaft of the printing wheels 242. The wheels 235 print on the upper face of the checks and the wheels 242 print upon the lower face of the record strip. The two sets of wheels being geared together, rotate together and exactly the same numbers are printed upon the checks and upon the record strip. The part 243 of the platen 151 forces the record strip against the ribbon on the type segments 200, 201 and 202 and the numbering wheels 242 for printing.

Figs. 5, 12, 16, 17 and 18 show the construction and arrangement of the dating and time printing mechanism while Fig. 20 shows the card or check 250 as it is printed on the bottom, the item being printed upon the upper surface. A series of printing wheels and segments are arranged on a common axis as shown in Figs. 17 and 18. Wheel 251 carries the type face for printing the numbers of the days of the months as shown at 251' in Fig. 20. The segment 252 prints the words "Day of month" with a pointer as shown at 252'. The segment 253 prints an index or pointer 253' for months. The wheel 254 prints a scale of minutes and names of the months as shown at 254'. The segment 255 prints the pointer 255' to indi-

cate the minute on the minute's scale. The segment 256 prints the pointer 256' for indicating the hour on the hour scale. The wheel 257 prints a scale of hours a. m. and p. m. as at 257' in Fig. 20. The pinion 260 on the hollow shaft 261 is driven by the oscillating segment 221 previously referred to which is in turn operated through the instrumentality of the movement of the arm 83 and shaft 84 and the link connection 162. The printing wheel 254 is secured to shaft 261 and rotates with it. The segment 253 is adjustably clamped to the shaft 261 in any suitable manner so that its angular position relative to the printing wheel 254 may be varied to bring its printing pointer opposite the proper month on the month's scale. This is set every month by hand. The printing segment 252 is securely clamped in any suitable manner upon the shaft 261 and prints the words "Day of month" and the pointer shown at 252' always in the same angular position so that it will come in the center of the check. The day printing wheel 251 is secured upon the sleeve 262 which is rotatably mounted in a part of the frame 3 and has a dial 263 at the left-hand side, which dial carries numbers corresponding to the numbers of the days of the months on the type wheel as shown in Fig. 12. A spider-like spring 264 presses against the dial 263 and the pinion 260 so as to frictionally hold the dial 263 and the printing wheel 251 in position. A stationary pointer 265 corresponds to the location of the pointer on the segment 252 when in its printing position, in order to set the dial 263 which is rotated in any suitable manner so that the number on the dial corresponding to the day of the month comes opposite the pointer 265. When thus arranged the corresponding number on the printing wheel 251 will be adjacent the pointer on the segment 252. This adjustment is effected when the drawer is closed and the parts of the mechanism are in their normal position.

Any suitable form of clock or time-piece is suitably mounted in the case 157. Preferably this clock is of the so called 24 hour type in which the hour shaft rotates once in each 24 hours. The minute shaft 267 of the clock serves as a centering and alining device for the time printing wheels and also carries the minute pointer printing segment 255. The hour shaft 268 is a hollow shaft as is customary in clock mechanism and carries the hour pointer printing segment 256. The hour number printing wheel 257 is carried by the sleeve 156 which is secured to the case of the clock. When the two pinions 158 and 260 are rotated simultaneously by their respective segmental gears 159 and 221, previously described, the printing wheels and segments and the time clock rotate together. The hour and minute index print-

ing segments are rotated by the clock relative to the minute and hour printing wheels so that the time of printing of each item is accurately recorded on the check.

- 5 The type wheels and segments just described are inked in suitable manner, for instance, by means of an inking roller 270 (see Fig. 5) carried by a pivoted spring arm or frame 271. A suitable yielding roller 272
 10 is rotatably mounted in the frame of the machine made for instance, of a yielding material so as to press yieldingly against the face of the printing wheels and segments and to constitute in conjunction therewith
 15 means for moving the check forwardly into a position to receive the imprint of the item and other characters as will be understood hereinafter.

The platen 275 for forcing the check up
 20 against the printing ribbon to receive the imprint of the item and other type is carried by two posts or plungers such as 276 secured to the platen in any suitable manner as for instance, in the recesses 277, 277 (see Fig. 25 11). These plungers 276 are pressed downwardly by suitable means as for instance, springs such as 278 (see Fig. 5) and held away from the printing ribbon. A suitable printing plate 214 (Fig. 5) may be secured
 30 to the under side of the web 273 (Fig. 17) to print advertisements upon the face of the check if desired. The narrow end 279 of the platen extends immediately beneath the item printing segments 203, 204, 205 previously described. The broad part of the platen 275 extends rearwardly beneath the web 273 for pressing the check against the bottom of the advertisement printing plate and the consecutive numbering printing
 40 wheels previously described and the classification printing wheels hereinafter described. The plate 280 is beneath the platen 275 when the mechanism is in its normal position. The cam 281 on the shaft 160 is adapted to press against the plate 280 and the latter in turn lifts the platen 275 and forces it upward so as to print the upper face of the check. This cam 281 is secured in such an angular position upon the shaft
 50 160 that it presses against the plate 280 and raises platen 275 at the very last part of the oscillation of the shaft 84 and after the feeding forward of the check has been completed so that the check is in its proper position on
 55 top of the platen 275.

The checks such as 250 are supplied in a magazine or chute 285 (see Figs. 28, 29, 30 and 32). The lower edges of the magazine are turned inwardly or flanged at 286 so as
 60 to support the edges of the checks. I have provided a tension or pressure device to force the checks down the magazine. A plate 287 rests upon the top of the pile of checks. This plate carries two pulleys or
 65 rollers 288 over which passes a flexible band

or cord 290. One end of this is secured as at 291 in Fig. 32 and the other end is secured to a spring winding drum 292 of any suitable character. In this way a substantially uniform pressure is maintained to hold the 70 checks down in the magazine. The checks as they come below the edge 293 of the magazine, are fed from the bottom of the magazine intermittently by a reciprocating feed device. The body consists of the plate 295 supported on the guides 296, 296 by means of a suitable anti-friction device which preferably consists of a series of balls such as 297 held in spaced relation by means of a perforated plate 298 through which the 80 lower surfaces of the balls project. The engaging edge of the feed member is formed by the lip 299 which is a part of a spring device 300 secured to the lower part of the plate 295. In the rear end of this engaging 85 member is a slot opening 301 in which a conical part 302 of a screw engages. By adjusting the screw in or out the conical surface by this engagement with the opening 301 will lower or raise the engaging lip 299 90 as the case may be in order to make it project above the plate 295 so as to correspond with the thickness of the check employed. A rack 304 pivotally secured to the feed plate 295 by means of the screw 305 engages 95 the teeth of the pinion 260 when the parts are in their feeding relation, the rack being held yieldingly in engagement with the pinion by means of a spring 306. Normally the position of the check feed device is as 100 shown in Fig. 5. When the movement of the reciprocating frame 27 releases the arm 83 as previously described and the segment 221 is oscillated, the check feeding device is moved to the rear until the bottom check 105 of the stack is engaged at its rear edge by the feed lip 299. When the arm 83 is moved to the rear again by means of the operation of the crank 164 the feed device moves forward and carries the check 250 between the 110 roller 272 and the time printing wheels. The continued rearward motion of the arm 83 rotating the time printing wheels moves the check forwardly on to the platen 275.

After the operation of the platen 275 the 115 check is discharged by a kicker 307. This kicker has its upper end slotted as shown in Fig. 31 so as to have a limited up and down movement on the screw or pivot bearing 308 and is under tension to be moved 120 forward by means of the spring 223 previously referred to. The lower end of the kicker is provided with one or more teeth or other suitably formed engaging means such as 309. This kicker has a projection 310 at 125 the left which is in the path of movement of the two pronged dog 311 pivotally carried by the oscillating segment 221. The dog is under the impulse of the spring 312 which presses it against stop 313 on the oscillating 130

segment 211. When the segment is rotated right-handed as just above mentioned the upper prong of the dog snaps by the projection 310. When the segment is oscillated 5 backward the dog engages the projection 310 on the kicker 307 and moves the latter to the position shown dotted in Fig. 12. The check is in the meantime being fed forward 10 by the roller 273 and the time printing wheels and when the dog 311 snaps to the left past the projection 310 the kicker by reason of its engagement with the upper 15 surface of the check is held in the rearward position until the check is released 20 from the pressure of the platen which has in the meantime come into operation. When the platen 275 releases its pressure on the check the kicker is drawn forwardly by the tension of the spring 223 and the check is 25 thus ejected from the machine. The check is guided between the parts of the frame 3, 3 so as to insure its being properly printed and delivered from the machine.

I have also provided mechanism by means 25 of which the check feeding device may be thrown out of operation when desired. A reciprocating member 315 suitably guided in the frame of the machine has a handle portion 316 suitable for manual engagement 30 by means of which the member 315 may be reciprocated. The rack 304 has a cam projection 317 adapted to be engaged by the nose 318 on the member 315. The spring frame 271 which carries the inking roller 270 has a projecting arm 319 in the slot 320 35 on the member 315. The plate 280 is pivotally carried by the member 315 being mounted upon the screw 321 so that when the cam 281 has operated as previously described 40 the plate 280 will have a certain freedom of movement permitting the pressure of the cam to be transmitted to the platen 275. When the member 315 is in the position shown in Fig. 5 the check feeding 45 and printing device is in the operative position but when the member 315 is drawn forward into the position shown in Fig. 12 the rack and the check feed plate are thrown out of operation, the inking roller 270 is re- 50 tracted and the plate 280 is withdrawn from the path of movement of the cam 281. In these positions there can be no movement of the platen 275 or of the feed device and the printing wheels simply rotate idly back 55 and forth. With the parts in the position shown in Fig. 12 in order to throw the check feeding and printing devices again into operation, the member 315 should be pushed to the rear when the drawer is opened other- 60 wise a false timing relation would be established. I prefer however to disengage and engage the feed while the drawer is closed.

At the right of the machine are arranged 65 a series of counters 330, 331, 332, 333 (see Figs. 1, 2, and 21) each of which has a

spring pressed pawl such as 334 adapted to be operated in order to actuate the counting dials. The arm 335 loosely pivoted on the shaft 336 is adapted to be swung upward and downward past the counters. A 70 plunger 337 or push key is longitudinally reciprocable in the arm 335 and carries a pin 338 projecting to the right as shown in Fig. 2 and adapted to co-act with one of the pawls 334 depending upon the angular position of the arm 335. The different counters are intended simply to register the number of operations of each character which have taken place. A rotatory drum indicator 340 has on its shaft the gear 341 80 engaged by the rack 342 which is held in suitable manner in engagement therewith. The arm 335 has a rearward projection 343 connected to the lower end of the rack 342. The drum 340 has upon it suitable words 85 indicating the character of the different transactions corresponding to the different sets of counters 330, 331, etc. As the arm 335 is swung so as to bring the pin 338 on the plunger or push key 337 into alignment with one of the slots such as 344, and the spring pressed pawl such as 334, the indicating drum is rotated to display the proper word. The plunger 337 is then pushed in and operates the counter to which 90 it is adjacent. This operation of the push key also releases the drawer and sets the classifying printing wheel 370 as described later. The shaft 336 has upon it a cam 345 (see Fig. 16) beneath the arm 194 of the 100 vertically moving frame 71 previously mentioned in connection with the release of the drawer. This shaft also has upon it a seg- 105 mental gear 346 (see Fig. 21) adapted to be engaged by a rack 347 which is carried by the rear end of the push key 337. When the push key is pushed inward the operation of the rack in conjunction with the gear segment oscillates the shaft 336 and the cam 345 and raises the arm 194 and the frame 110 71 and thus releases the drawer and the other operations which take place in conjunction with the release of the drawer follow as previously described. The rack 347 in the position shown in Fig. 21 is of such 115 length that its rear end does not engage the teeth of the segment 346. The movement of the arm 335 alone does not therefore cause any interconnection between the rack and segmental gear but when the push key 337 is pushed inward the teeth of the rack 347 immediately begin to engage the teeth of the segment. The slots 344 adjacent the counter pawls and the teeth of the rack and segment are so designed and located 120 with relation to each other that the rack will always properly engage the teeth of the segment when the push key is pushed inward.

In order to compel the complete move- 130

ment inward and outward of the push key 337 I have provided a pawl 350 to engage the teeth of the rack 347. This pawl is under tension of the spring 351 (see Fig. 2). 5 The arm 335 carries a slide 352 which has limited motion thereon and an inclined shoulder 353 adapted to engage the front end of the pawl 350. When the push key is pushed inward the rack slides by the pawl 10 tooth which yields for this purpose but the rack cannot be pulled outward until the inward motion of the push key is completed and the screw 354 carried by the push key engages the slide 352 and forces its shoulder 15 353 against the pawl and disengages the pawl from the rack. The rear end of the spring 351 (see Fig. 2.) is secured to a collar 355 on the end of the push key so that when the push key is released the tension of the spring 351 forces the push key 20 outward. The pawl being then out of engagement with the rack by reason of the engagement of the shoulder 353 with the pawl as just described, the push key is free to 25 be moved to its full extent forwardly into its normal position. When the push key 337 reaches its outward position the screw 354 reaches the end of the slot in the slide 352 and retracts the slide from the pawl 350 30 so that the spring 351 again throws the pawl into engagement with the teeth of the rack 347.

In order to prevent registration on the cash totalizing device, previously described, 35 while the classification registration is taking place I have provided a notched segment 360 (see Fig. 2), the notches of which are in alignment with the notches in the segment 26 when the classification mechanism is not being used. This segment 360 has a limited movement with relation to the segment 26 by means of a pin and slot connection as shown in Fig. 21. The right-hand end of the segment 360 has a projection 361 which is beveled as shown in Fig. 2. Secured to the operating arm 335 is another arm 363 which projects downwardly and has an inclined cam-like portion 364 adapted to co-act with the beveled projection 362 on the notched 45 segment 360. The normal position of the arm 335 is as shown dotted in Fig. 21. When the arm is moved downwardly so as to bring it in position to operate the push key 337 in conjunction with any one of the counters the cam-like member 364 engages the beveled projection 362 and oscillates the segment 360 sufficiently to bring its notches out of alignment with the notches of the plate 26 as shown in Fig. 2. In this position it is 50 impossible to operate the reciprocating frame 27 and hence the push key 75 and cash registering mechanism cannot be operated. When the arm 335 is returned to its normal upper position the spring 365 (see Fig. 2) 55 returns the segment to its normal position in

which its notches are in alignment with the notches of the segment 26. When the transaction is other than a cash transaction the character is printed on the check. The printing wheel 370 (see Fig. 17) is secured 70 to gear 371 and both are rotatable on the shaft 372 being rotatable independently of the shaft. A gear 373 is fast on the shaft 374 and meshes with gear 371. The shaft 374 has at the right a pinion 375 in mesh 75 with the segmental gear or rack 376 carried by the classifying arm 335. When the classifying arm has swung on its pivot the interaction of the rack 376 with the pinion 375 rotates shaft 374 and by connection between 80 gear 373 and 371 rotates the printing wheel 370 so as to bring its type face corresponding to the character of transaction to be counted into position for printing above the check. The operation of the printing platen 85 275 forces the check up against the ribbon beneath the printing wheel 370 and prints the character of the transaction registered accordingly on the check.

Supposing that the amount indicated in 90 Fig. 1 of \$10.45 was "cash" instead of being "paid out" transaction it would be ordinarily registered by the cash registering mechanism by means of the push key 75. In case the transaction was "paid out" the operating 95 arm and knob would be set in the position shown in Fig. 1, the printing frames would all be set up correspondingly and the indicating dials would indicate the amount. The classifying mechanism would then be 100 moved into the position shown in Fig. 1 so that the indicator drum 340 would show the words "paid out" and the operating arm 335 and push key 337 would be in the position shown in Fig. 1. The movement of the arm 335 to the position shown will have rotated the printing wheel 370 into position to bring the type, for instance, Pd. into printing position immediately above the check. When the push key is pushed inward the counter 105 333 moves forward one number indicating that one additional "paid out" transaction has been made. The operation of the arm 335 moves the notched segment 360 into a position to prevent operation of the cash 110 registering mechanism. The operation of the push key 337 releases the drawer, as above described, to permit the change to be made. When the drawer is released the arm 73 moves forward, the shaft 84 oscillates and the operation of the record strip and check feed and the feeding of the inking ribbon as previously described, follows. The operation of the crank 164 as previously described closes the drawer and operates the 115 printing platen so as to print the amounts, symbols, time, date, numbers, etc.

Any suitable form of stop device may be employed as is customary to prevent the drawer from being thrown out or accident- 120 125 130

- ally removed from the case. The forward movement of the arm 83 is limited by the length of the slot in the case 6 (see Fig. 2). What I claim is:—
- 5 1. In a machine of the character described, a laterally movable setting arm and a knob carried thereby and rotatable on an axis extending transverse to the direction of lateral movement and an operating key carried by said arm and having a movement independent thereof.
  - 10 2. In a machine of the character described, a laterally movable setting arm and a rotatable and longitudinally movable setting knob carried thereby.
  - 15 3. In a machine of the character described, a register, a rotatable and longitudinally reciprocable knob, means for preventing rotation when the knob is in its normal longitudinal position and preventing reciprocation when the knob is out of its normal rotation position and mechanism operable by said knob to totalize said register in an adding operation.
  - 20 4. In a machine of the character described, a laterally movable setting arm, a rotatable and longitudinally movable setting knob carried thereby and interlocking parts to prevent rotation of said knob except when moved longitudinally from its neutral longitudinal position and to prevent longitudinal movement of said knob except when in its neutral rotated position.
  - 25 5. In a machine of the character described, a laterally movable setting arm, a rotatable setting knob carried thereby and a push key carried by said arm and having an independent movement.
  - 30 6. In a machine of the character described, a laterally movable setting arm, a rotatable and longitudinally movable knob carried thereby and a push key carried by said arm.
  - 35 7. In a machine of the character described, a laterally movable setting arm, an independently rotatable setting knob carried thereby and interlocking parts to prevent lateral motion of said arm when said knob is pushed in.
  - 40 8. In a machine of the character described, a swinging setting arm movable laterally, a longitudinally movable push key carried thereby and interlocking parts to prevent lateral motion of said arm when the push key is pushed in.
  - 45 9. In a machine of the character described, a laterally movable setting member adapted to be adjusted to different positions and a push key carried thereby and movable longitudinally thereof and registering mechanism operated by said push key.
  - 50 10. In a machine of the character described, a movable setting arm, a cents setting scale adjacent the path of movement thereof, a rotatable setting knob carried by
  - 55 said arm and a dollar setting dial carried by said knob.
  - 60 11. In a machine of the character described, a laterally movable arm, a transversely rotatable knob carried thereby and registering mechanism affected by said arm and knob.
  - 65 12. In a machine of the character described, a laterally movable arm, a rotatable knob carried thereby, registering mechanism affected by said arm and knob, a push key and a shutter moved by said push key.
  - 70 13. In a machine of the character described, a registering and an indicating mechanism, a movable setting arm therefor, a shutter and an operating key for said shutter carried by said setting arm for disclosing the indication and operable after the arm and indicating mechanism are set.
  - 75 14. In a machine of the character described, a registering and an indicating member, a shutter for said indicator, a setting arm for said indicating member and said register, an operating key for said shutter and means for releasing said shutter when the arm is moved after an indication.
  - 80 15. In a machine of the character described, a register, an indicator, a shutter, a catch for said shutter, an arm for setting the indicator and register, a key for moving the shutter independently of the movement of the arm, said arm releasing said catch.
  - 85 16. In a machine of the character described, a laterally movable setting member adjustable to different positions, a push key carried thereby and movable longitudinally in relation thereto, an indicator adapted to be moved by said setting member and a registering device to be affected by the longitudinal movement of said push key.
  - 90 17. In a machine of the character described, a setting arm, registering mechanism carried thereby and an operating key carried by said arm for said registering mechanism.
  - 95 18. Registering mechanism comprising a movable arm, a register carried thereby and set by the movement of said arm and a key carried by said arm for operating said register.
  - 100 19. Registering mechanism comprising a register, an operating part therefor, means for setting said part and a reciprocating member for releasing and operating said operating part.
  - 105 20. Registering mechanism, a rotatable setting knob, and a reciprocal release key, said mechanism being operable upon backward rotation of the setting knob after the action of said release key, to totalize said register in an adding operation.
  - 110 21. Registering mechanism comprising, a register device, a setting knob, and a release key, said register being operated by said

knob to totalize said register in an adding operation, after the release by said key.

22. In a registering mechanism, a registering member rotatable in one direction only, a setting member having a limited rotative movement about the same axis, a transmitting member having a limited rotative movement relative to said setting member and on the same axis, a spring connecting 5 said setting and transmitting member and a pawl and ratchet connection between said transmitting member and said registering member.

23. In a machine of the character described, two registering mechanisms, an arm for setting one registering mechanism, means for locking the other mechanism, a push key for operating said registering mechanism and releasing the second registering mechanism and a knob for setting and operating the second registering mechanism.

24. Registering mechanism comprising, a movable arm, two registers carried thereby, one register being set by the movement of said arm, a key for operating said register and a knob for setting and operating the other register when the key has been operated.

30 25. Registering mechanism, comprising a movable arm, two registers carried thereby, one register being set by the movement of said arm, a key for operating said register, a knob for setting and for operating 35 the other register when the key has been operated and means for carrying forward from one register to the other.

40 26. In a machine of the character described, a swinging arm, registering mechanism carried thereon and including a wheel having a notch and ratchet teeth and interlocking devices for preventing the swinging of said arm and for engaging with said wheel.

45 27. Registering mechanism including, counters, a reciprocating push key, a movable arm carrying said counters and said key, a rotatable cam operated by said push key and an operating connection between 50 said cam and said counters.

55 28. In a registering mechanism, a swinging arm, counters carried thereon, a notched wheel carried by said arm and rotatable as the arm is swung and a yielding device engaging said wheel to tend to hold it and the arm in definite positions.

60 29. Registering mechanism comprising, a swinging arm, two registers carried thereby one of said registers being set by the movement of said arm, a rotatable knob for setting and operating the other register, and a push key for operating the first register, and releasing the second register.

30. In a machine of the character de-

scribed, a stationary gear segment, a swinging arm, a gear carried thereby and meshing with said segment, a notched wheel rotatable with said gear and a yielding device engaging said wheel to tend to hold it in definite angular positions.

70 31. In a machine of the character described, a laterally movable arm, a rotatable knob carried thereby and printing frames set by said arm and knob.

32. In a machine of the character described, a laterally movable arm, a printing frame set thereby, a rotatable and longitudinally movable operating knob carried by said arm, and a printing frame connected thereto when the knob is moved longitudinally.

75 33. In a machine of the character described, a laterally movable arm, a rotatable and longitudinally movable knob carried thereby and interlocking parts to prevent rotation of said knob except when moved longitudinally from its neutral longitudinal position and to prevent longitudinal movement of said knob except when in its neutral rotated position and printing 80 frames moved by said arm and knob.

34. In a machine of the character described, a laterally movable arm, a rotatable knob carried thereby, printing frames set by said arm and knob and a push key carried by said arm.

85 35. In a machine of the character described, a laterally movable arm, a rotatable and longitudinally movable knob carried thereby, printing frames set by said arm and 100 knob, platens adapted to co-act therewith and a push key carried by said arm for releasing said platens.

105 36. In a machine of the character described, a printing frame, a platen to co-operate therewith, a movable setting member adapted to be adjusted to different positions and a push key carried thereby and movable longitudinally thereof for releasing said platen.

110 37. In a machine of the character described, a cents printing frame, a movable setting arm therefor, a cents setting scale adjacent the path of movement thereof, a dollar printing frame, a rotatable knob 115 therefor carried by said arm and a dollar setting dial carried by said knob.

38. In a machine of the character described, a laterally movable arm, a rotatable knob carried thereby and indicating and 120 printing mechanism set by said arm and knob.

125 39. In a machine of the character described, a movable arm, a cents setting scale adjacent the path of movement thereof, a rotatable knob carried by said arm, a dollar setting dial carried by said knob, a cents indicating dial and a cents printing frame set

50. In a machine of the character described, a normally stationary gear, mechanism connected thereto, a swinging setting arm movable with relation thereto, a toothed member carried by said arm and normally 70 out of engagement but adapted to mesh with said gear and an operating member carried by said arm for throwing said toothed member into mesh with said gear to operate the same. 75
51. Classifying mechanism comprising a counter having a lever, a plate with a notch adjacent said lever, a setting arm movable past said counter, a push key carried by said arm and having a projection adapted to enter said notch in said plate to engage the lever and operate the counter. 80
52. In a machine of the character described, printing mechanism, cash totalizing mechanism, setting mechanism, means for effecting the printing, means for operating the totalizing mechanism and two laterally and longitudinally movable keys for releasing the printing mechanism, means operated by one key to release the totalizing mechanism and means to prevent operation of the totalizing mechanism when the other key is operated. 85 90
53. In a machine of the character described, a swinging arm, a reciprocating member longitudinally movable thereon, a cash drawer, and a latch bolt therefor retracted by the movement of said reciprocating member. 95
54. In a machine of the character described, a swinging arm, a reciprocating member longitudinally movable thereon, a cash drawer, a latch bolt therefor retracted by the movement of said reciprocating member and a catch for holding said bolt 100 105 retracted.
55. In a machine of the character described, a swinging arm, a reciprocating member longitudinally movable thereon, a cash drawer, a latch bolt therefor retracted by the movement of said reciprocating member, a catch for holding said bolt and an arm for releasing said catch. 110
56. In a machine of the character described, a swinging arm, a reciprocating member longitudinally movable thereon, a cash drawer, a latch bolt therefor retracted by the movement of said reciprocating member, a catch for holding said bolt retracted, an arm for releasing said catch and 115 a spring for impelling said arm away from said catch. 120
57. In a machine of the character described, a swinging arm, a reciprocating member longitudinally movable thereon, a cash drawer, a latch bolt therefor retracted by the movement of said reciprocating member, a catch for holding said bolt retracted, an arm for releasing said catch, a spring for impelling said arm away from 125 130
50. In a machine of the character described, a movable setting member and adjustable to different positions, a push key carried thereby and movable longitudinally in relation thereto, an indicator and a printing frame adapted to be moved by said setting member and a registering device affected by the movements of said setting member and said push key. 10
51. In a machine of the character described, sets of two parallel type bars oppositely faced for duplicate printing and mechanism for moving matter to be printed on, transversely to said bars and longitudinally of same. 15
52. In a machine of the character described, a swinging printing frame having type faces, a platen and an alining device coacting with said frame and both movable in directions parallel with the axis of the frame. 20
53. In a cash register, sets of two parallel type bars oppositely faced and movable together for duplicate printing, and mechanism for moving matter to be printed on, transversely of said bars and mechanism for moving matter to be printed on, longitudinally of same. 25
54. In a machine of the character described, strip feeding mechanism including a ratchet, strip printing mechanism including a reciprocating platen, a spring finger carried by the platen for operating said ratchet and a plate acting as a guide for said finger. 30
55. In a machine of the character described, strip feeding mechanism including a ratchet, a stationary plate having a concave guide surface adjacent thereto and a spring operating finger to engage said ratchet and adapted to be disengaged by said plate. 40
56. In a machine of the character described, two sets of item printing devices, duplicate connected consecutive numbering devices, one platen for coacting with one set of item printing devices and one numbering device and a second platen for coacting with the other set of item printing devices and the other numbering device. 50
57. In a machine of the character described, a counter, a classifying arm movable with relation thereto, and a key carried by said arm for operating said counter. 55
58. In a machine of the character described, a classifying arm, an indicator operated thereby, a shutter, and a key carried by said arm for moving said shutter. 60
59. In a machine of the character described, an indicator, a counter, a movable arm for setting said indicator and a push key movable with and with relation to said arm for operating said counter. 65

- said catch and a crank for moving the arm against the power of the spring to engage said catch.
58. In a machine of the character described, a driving member, an arm operable therewith, a movable abutment for said arm adapted to be moved with said arm and adapted to be retracted when said arm is retracted, said arm having a limited range of movement without moving said abutment and a printing device operated when the arm and abutment are being retracted, and retracted upon the return free movement of the arm while the abutment is stationary.
59. In a machine of the character described, a driving member, an arm operable therewith, a movable abutment therefor, a bolt normally holding said abutment and a catch for said bolt.
60. In a machine of the character described, a driving member, an arm operable therewith, a movable abutment therefor, a bolt normally holding said abutment, and a catch for said bolt adapted to be released by said arm.
61. In a machine of the character described, a swinging arm, a reciprocating frame carried thereby, a stationary notched segment adapted to be engaged by said frame when reciprocated, a classifying device and a second notched segment normally registering with the first but adapted to be moved by the operation of the classifying device so as to prevent the operation of said reciprocating frame.
62. In a machine of the character described, the combination of a cash drawer and a catch therefor, a cam having its ends beveled, oppositely faced ratchet teeth at opposite sides of said cam, a reciprocating member for releasing said catch, a two-armed pawl movable therewith adapted to engage the ratchet teeth and a finger adapted to engage said cam for tilting said pawl so as to compel complete reciprocation of said member.
63. In a machine of the character described, a drawer, a catch therefor, a gear connected to release said catch, a reciprocating rack carried thereby and adapted to mesh with said rack, a pivoted pawl carried by said arm and normally engaging the teeth of said rack, a slide carried by said arm and having a pin and slot connection with said rack and adapted to engage said pawl to disengage it from said rack.
64. In a machine of the character described, register printing mechanism, a pivoted crank arm for operating said mechanism, a pivoted two-pronged pawl carried thereby, a two-notched catch engaging a shoulder on said pawl, two oppositely arranged sets of ratchet teeth adapted to be engaged by the prongs of said pawl and a shoulder between said sets to reverse said pawl.
65. In a machine of the character described, indicating mechanism including a rotatable dial bearing on its face the figures 0, 5, in succession and a second dial bearing on its face the figures 1, 2, 3, etc., and an intermittent driving connection between said dials.
66. In a registering mechanism, a stationary track member, an arm movable past said track, a wheel carried thereby engaging said track member, a register movable with said arm and mechanism connecting said wheel and register for operating said register according to the rotation of said wheel.
67. In a machine of the character described, in combination, a track member and a carrier, one of said members being movable with relation to the other, a wheel rotatable on the carrier in engagement with the track, a detent member operable with said wheel and a yielding device coacting with said detent member to yieldingly hold said wheel.
68. In a machine of the character described in combination, a track member and a carrier, one of said members being movable with relation to the other, a wheel rotatable on the carrier in engagement with the track, registering mechanism adapted to be affected by the rotation of said wheel, a detent member operable with said wheel and a yielding device coacting with said detent member to yieldingly hold said wheel.
69. In a machine of the character described, an actuating knob movable laterally in the plane of a fixed arc rectilinearly in the same plane and rotatable transversely thereto.
70. In a machine of the character described, a carrier, an adjustable actuating member movable laterally and having a sliding relation to said carrier, said carrier having various defined positions adjacent the lateral path of movement of said sliding member whereat the said member may be slid inwardly.
71. In a machine of the character described, an actuating knob adjustable laterally in the plane of a fixed arc, various defined positions on said arc wherein the said knob may be moved rectilinearly, means defining such positions and means operating to prevent rectilinear movement of said knob between said positions.
72. In a machine of the character described, an actuating member adjustable laterally in the plane of a fixed arc, various defined converging angular positions on said arc whereat said member may be moved longitudinally on converging rectilinear lines.

73. In a machine of the character described, an operating knob having a pivoted support whereon it may be moved through a limited arc laterally, means for limiting said arc and bearings whereon it may be moved rotatably and longitudinally.

74. In a machine of the character described, an operating knob having bearings whereon it may be moved laterally through a horizontal plane, means for fixing said plane and bearings whereon it may be moved longitudinally in the same plane.

75. In a machine of the character described, a register, an operating knob having bearings whereon it may be moved through a single fixed arc and bearings whereon it may be moved rotatably and longitudinally, a hand operable laterally and longitudinally movable member adapted to move in said knob and having means whereby the lateral movement of said member sets the register and the longitudinal movement operates the same.

76. In a machine of the character described, a hand operable member movable laterally, a scale adjacent its path of movement, designated indicating positions, a reciprocating member adapted to be operated by an inward push and release of the hand when the laterally movable member is in an indicated position and means for preventing operation of said member when out of correct indicating position.

77. In a machine of the character described, a movable setting arm, a fixed scale of figures adjacent the path of movement thereof, a rotatable knob carried by said arm and a second scale of figures rotatable with said knob and adjacent said first scale.

78. In a machine of the character described, a laterally movable arm, a scale of figures adjacent the path of movement thereof, a rotatable knob carried by said arm, a second scale of figures rotatable with said knob and adjacent said first scale.

79. In a machine of the character described, a laterally movable arm, a rotatable knob carried thereby, indicating members affected by said arm and knob, a push key and a shutter moved by said push key to expose the indicators.

80. In a machine of the character described, an operating knob, laterally, rotatively and longitudinally movable and means for preventing lateral movement thereof when the same is out of its normal longitudinal position and mechanism operated by said lateral and rotative movements.

81. In a machine of the character described, two scales of figures arranged on adjacent arcs transversely set in relation to one another, one of said scales having a fixed position and the other of said scales having an adjustable relation to said first scale.

82. In a machine of the character de-

scribed, a scale of figures having a fixed position and a second scale of figures adjacent to said first scale and having a lateral and a rotative adjustment relative to the fixed scale.

83. In a machine of the character described, a fixed scale of figures, a second and movable scale of figures adjacent said fixed scale, rotative indicators having relatively corresponding figures to said scales and means whereby the adjustment of the movable scale relatively to the fixed scale effects a similar relative adjustment of the indicators.

84. An operating adjustable member movable through a fixed arc, defined positions on said arc whereat said member may be moved inwardly, a cash drawer, a latch bolt therefor, retracted by the inward movement of said movable member and a catch for holding said bolt retracted.

85. In a machine of the character described, a rotatable indicator and a lock therefor, a movable abutment and a lock for said abutment, a hand operable key and means for operating said abutment lock by said key, a reciprocating member movable by said key and means controlled by same for locking said indicator.

86. In a machine of the character described, an indicator, a counter, a pivoted member for setting and operating said indicator and counter, said member comprising essentially two elements movable together and one of said elements movable longitudinally in relation to the other.

87. In a machine of the character described, an indicator, a counter and a movable arm, the latter comprising two essential members movable together, and one of said members being movable longitudinally in relation to the other, means for concealing said indicator and means whereby when the longitudinally movable member is operative longitudinally, said indicator is disclosed and said counter is operated.

88. In a machine of the character described, an indicator, a counter and a movable arm, the latter comprising two essential members, one of said members being movable longitudinally in relation to the other, means for concealing said indicator and means whereby when the longitudinally movable member is operated longitudinally, said indicator is disclosed and said counter is operated.

89. In a machine of the character described, a register, an indicator, a setting member laterally movable, a hand operable actuating member movable with and with relation to said setting member for actuating said register, connecting means between said actuating member and register, a reciprocating member for locking said indicator and means whereby when said actuating

- member is operated fully said reciprocating member locks and releases said indicator.
90. In a machine of the character described, a register and a rotatable indicator, a common setting member therefor comprising essentially two parts movable together in one direction, and one part longitudinally movable in relation to the other, a reciprocating member adapted to lock said indicator and operable by said longitudinally movable part.
91. In a machine of the character described, a register and a rotatable indicator, a common setting member, a hand operable member movable with and with relation to said setting member, a reciprocating member adapted to lock said indicator and operable by said hand operable member.
92. In a machine of the character described, a rotative indicator, a setting member therefor, a key member carried by said setting member, a locking member for said indicator, a full stroke device operating in conjunction with the setting member, the key member and the locking member to effect complete operation of the key member and complete reciprocation of the locking member.
93. In a machine of the character described, rotative indicators, a setting member comprising essentially a key element and a carrier therefor, a reciprocating locking member movable by said key element and means whereby the reciprocating member locks and unlocks the said indicators at each operation of the key element.
94. In a machine of the character described, a register, a setting arm laterally movable, and hand operable actuating members for said register movable with said arm and having rectilinear movement independently thereof.
95. In a machine of the character described, a register, a setting arm therefor laterally movable, and a member for actuating said register movable with said arm and movable longitudinally in relation thereto to actuate said register.
96. In a cash register, the combination with registering and indicating mechanism, of an inwardly projected and longitudinally operable arm, affecting said registering mechanism, a full stroke device movable with said arm and a locking device for said indicating mechanism operated by said arm and controlled by said full stroke device.
97. In a cash register, the combination with registering and indicating mechanism, of a longitudinally movable arm, a full stroke device for controlling said arm, a locking device for said indicating mechanism operated by said arm and means connecting said arm with said registering and indicating mechanisms.
98. In a cash register, the combination with mechanism including a movable setting member and a key element and full stroke device thereon, of a register operated directly by said mechanism.
99. In a cash register, the combination with mechanism including a movable setting arm and a key element and full stroke device movable therewith, of a reciprocating locking member for certain of said parts, a register and an indicator all operable by said mechanism.
100. In a cash register, the combination with mechanism including a movable setting arm, an independently movable key element, and a full stroke device movable therewith, of a reciprocating locking member for certain of said parts, a register and an indicator all operated by said mechanism.
101. In a cash register, the combination with mechanism including a movable setting arm and a longitudinally movable key element movable therewith, of a reciprocating locking member for certain of said parts, an indicator and a register all operable by said mechanism.
102. In a cash register, the combination with mechanism including a movable setting member and a key element movable therewith, of a reciprocating locking member for certain of said parts, a full stroke device, an indicator and a register all operable by said mechanism.
103. In a cash register, the combination with mechanism including a movable setting member, a key element and a full stroke device movable with the setting member, of a reciprocating locking member for certain of said parts, an indicator and a register operable by said mechanism.
104. In a machine of the character described, a register, an indicator and a locking member for said indicator, a movable member for operating all said members, said movable member comprising essentially two elements movable together, and one of said elements movable longitudinally in relation to the other.
105. In a cash register, the combination with a register, of a movable setting arm and hand operable actuating elements for the register movable with said arm having reciprocable movement independently thereof.
106. In a cash register, a normally locked movable abutment, and a driving crank normally held by same, a member controlled by said crank, a motor impelling engagement between said crank controlled member and said abutment, a release key for said abutment, said motor serving upon release of said abutment to move same and rotate said crank a limited degree in one direction and means whereby upon the re-

verse movement of said crank back to normal position, said abutment is returned to normal locked position.

107. In a cash register, the combination 5 with a driving shaft and mechanism operated thereby, of an arm movable with said shaft, a reciprocable abutment normally locked and in engagement with said arm, means for rotating said shaft, means for 10 releasing said abutment and means for reciprocating said abutment by said arm.

108. In a cash register, the combination 15 with a driving crank and mechanism operated thereby, of a reciprocable abutment normally locked, a motor for impelling rotation of said crank upon the release of said abutment, means for releasing same and means for reciprocating said abutment by 20 said crank.

109. In a machine of the character described, registering mechanism, rotatable indicating mechanism and locking mechanism therefor, a movable member for operating said mechanisms, including multiple 25 actuating elements movable with said operating member and having reciprocable movements independently thereof.

110. In a machine of the character described, a register, a movable setting member for said register, said member comprising 30 essentially two elements movable together, one of said elements movable longitudinally in relation to the other, an indicator comprising two rotary members representing respectively units and tens and 35

adapted to be set by an element of the said movable setting member.

111. In a machine of the character described, an indicator, a counter, a movable member for setting and operating said indicator and counter, said member comprising 40 essentially two elements movable together, one of said elements movable longitudinally in relation to the other and a locking device for said indicator operable by an element of said movable setting member. 45

112. In a machine of the character described, a register, a rotatable indicator and a locking member for said indicator, a movable member adapted to operate all said 50 members, a longitudinally movable key element movable with said operating member and adapted to operate said register and said locking member.

113. In a machine of the character described, a rotatable indicator, a counter, a movable member for setting and operating said indicator and counter, said member comprising essentially two elements movable together, one of said elements movable 55 longitudinally in relation to the other, a member having spaced notches and a locking member operable by one of said elements and adapted to engage said notches and lock said indicator. 60
